UNITED STATES PATENT OFFICE.

JAMES A. BARR, OF NEBRASKA CITY, NEBRASKA, ASSIGNOR OF ONE-HALF
TO GEORGE W. EISER, OF SAME PLACE.

WINDOW.

SPECIFICATION forming part of Letters Patent No. 683,588, dated October 1, 1901.

Application filed May 20, 1898. Serial No. 681,206. (No model.)

To all whom it may concern:

Be it known that I, JAMES A. BARR, residing at Nebraska City, in the county of Otoe and State of Nebraska, have invented certain useful Improvements in Windows; and I do hereby declare that the following is a full, clear, and exact description of the invention, such as will enable others skilled in the art to which it appertains to make and use the same, reference being had to the accompanying drawings, which form a part of this specification.

This invention relates to a new and novel improvement in ventilators for windows.

15 The object of my invention is to provide a ventilator which will prevent the frosting of window-panes, my invention being adapted to be used more particularly in connection with show-windows.

20 In the accompanying drawings, Figure 1 shows a broken view of a show-window provided with my improved ventilator. Fig. 2 shows a central sectional view disclosing the arrangements of the various instrumentalities, while Fig. 3 shows a view illustrating the method of positioning the vertical ventilator-border.

25 My invention embodies, essentially, a scalloped ventilated border, upon which the lower edge of the window-pane rests, in combination with a second vertical ventilator-strip, and a shield provided with a suitable valve, by means of which the ingress and egress of air may be regulated.

30 In the accompanying drawings, A represents the side portions, and B the sills, of an ordinary show-window, within which the plate-glass C is positioned, and which plate C rests upon a scalloped ventilator-strip 4, of metal or of any other suitable material, so as to provide a series of ventilating-openings, as is clearly shown in Figs. 1 and 2. This strip is positioned horizontally, and adjacent thereto and in juxtaposition therewith is a second 35 ventilating-strip 5, positioned vertically, scalloped and of any suitable size or material, so that the air coming through the scalloped horizontal strip is permitted a ready escape to the inside of the window upon C by virtue

of this ventilator-strip 5, as will be more fully understood in referring to Figs. 2 and 3. These ventilated strips 4 and 5 are two independent pieces.

40 Show-windows in winter time are very apt to become frosted, so that the goods displayed cannot be seen. To provide a means whereby this frosting of the window-panes may be obviated is the aim of my invention.

To support the ventilator-strip, I provide the bottom plate 2, provided with the upwardly and outwardly extending portion 3, upon which both the horizontal ventilator-strip and the vertical ventilator-strip rest. Both the horizontal and the vertical ventilator-strips are intended to come upon the inside of the window. Upon the outside I provide a shield 7, as shown in Fig. 2, which shield is provided with openings 10, and a sliding valve is operated by means of a button 9, so that the draft may be regulated, the object of course being to provide equal 45 temperature upon both sides of the plate C, which prevents the condensation of the vapors and consequent frosting of the windows. While I have shown the ventilator-strip so 50 scalloped, it is of course understood that any other shape could be imparted to the strips without departing from the spirit of my invention.

Having thus described my said invention, what I claim as new, and desire to secure by United States Letters Patent, is—

1. The combination with a window-light, of a horizontal scalloped ventilator-strip, a vertical scalloped ventilator-strip positioned adjacent to said horizontal strip, and a plate supporting both of said ventilator-strips, as and for the purpose set forth.

2. The combination with a window-light, of a horizontal scalloped ventilator-strip, supporting said window, a vertical scalloped ventilator-strip, positioned adjacent to said horizontal strip, a base-plate to support both of said ventilator-strips, and a shield, covering said horizontal ventilator-strip, provided with suitable valved escape-ways, as and for the purpose set forth.

3. In a window-ventilator of the character

described, the combination with a base-plate provided with a vertical extension, of a horizontal ventilator-strip upon said plate and supporting the window-light, a vertical ventilator-strip positioned between said window-light and horizontal ventilator-strip upon one side, and said vertical extension upon the other side, and a shield to cover said horizon-

tal ventilator-strip upon the side opposite said vertical extension.

In testimony whereof I affix my signature in presence of two witnesses.

JAMES A. BARR.
